UNITED STATES PATENT OFFICE.

ANKER S. LYHNE, OF BRIDGEPORT, CONNECTICUT.

VANITY BOX.

Application filed December 10, 1924. Serial No. 754,986.

This invention relates to vanity boxes of the type which comprises, usually, a thin metal casing which contains powder, a puff to be used with the powder and a mirror, and has for an object to provide an improved holder for the powder which may be applied as an insert for boxes of this type in place of the usual powder compact. Vanity boxes of this type in which the powder is used in the form of a compact are unsatisfactory to a great many people because they cannot always secure the particular type or brand of powder they desire in the compact form.

It is, therefore, an object of this present invention to provide an improved container for loose powder which may be inserted in the box in place of the usual compact, and which may be easily and quickly filled with the brand or type of powder desired in the loose form.

It is also an object of the invention to provide an improved and simple construction of the container, which, although it may be easily opened for changing or renewing the powder, may be as easily and quickly closed, and when closed will provide a perfect seal which will prevent leakage of the powder from the container.

With the foregoing and other objects in view, I have devised the construction illustrated in the accompanying drawing forming a part of this specification, similar reference characters being employed throughout the various figures to indicate corresponding elements. In this drawing,

Fig. 1 is a transverse section on an enlarged scale through a vanity box with my improved powder container and insert in position with the box closed.

Fig. 2 is a partial side elevation and partial section of the same in open position.

Fig. 3 is a top plan view of the box in open position.

Fig. 4 is a top plan view of the powder container, a portion of the cover or closure being broken away.

Fig. 5 is a section through the elements of the powder container in separated relation, the section being substantially on line 5-5 of Fig. 4, and

Fig. 6 is a section on an enlarged scale of a portion of the container, the section being substantially on line 6-6 of Fig. 4.

The box comprises the usual body member 10 and cover member 11 of any suitable

material, such as sheet metal, connected by the usual hinge 12. The upper portion of the sides of the body are preferably reduced somewhat as shown at 13 so as to fit into or be embraced by the cover section when closed to give a neat and attractive appearance, and also to give a better and tighter closure. The cover may contain a mirror 14 secured therein by any suitable means such as a ring 15 frictionally engaging the sides of the cover.

In the present construction, instead of a powder compact being mounted in the body member, I provide a container for loose powder in the form of an insert to be placed in this member. The preferred construction of this insert comprises a lower cupped member 16 having a fairly wide laterally extending flange 17 about the periphery of the upper edge of the cup, and to give a neat and attractive appearance and also to strengthen this member the flange extends downwardly to provide a substantially cylindrical outer wall 18 terminating substantially in the same plane as the bottom of the cup, so that when the container is inserted in the body of the box the bottom of the cup and the edge of this wall will rest on the bottom of the body member. After the loose powder, indicated at 19, is placed in the cup, the cup is closed by a cover or closure 20. This cover or closure has a depressed central body portion as shown at 21 with an upright edge 22 about this body portion, and is also provided with a laterally extending flange 23 about the upper edge of this upright portion. The diameter of the upright portion 22 is such as to fit tightly in the upper open end of the cupped member 16 and the flange 23 rests on the flange 17. This construction and arrangement forms an effective seal between the two members through which the loose powder will not pass, and therefore, cannot leak from the container as the box is carried in the pocket or handbag. It is difficult for the powder to pass through the tight closure between the upright portion 22 and the cup, and the relatively wide contact surfaces between the two flanges 17 and 23 effectively preventing the passage of any powder which may pass from the container to a position between these flanges.

As shown in Figs. 1 and 5 the central portion 21 of the cover or closure is arched slightly and provided with any desired num-

ber of openings adjacent the center of the cover, and this closure is made of flexible, resilient metal so that with a slight pressure it may be depressed, as indicated to the dotted line position, Fig. 1, by pressing downwardly on the puff 25 to cause some of the loose powder to pass through the openings 24 and be taken up by the puff. When the pressure is released the resiliency of the cover will cause it to spring back to the upper or original position. To form an effective closure or seal to prevent powder passing through the openings 24 into the upper part of the box as it is being carried an upwardly extending rib 26 is formed about these openings upon which the puff rests as shown in Fig. 1, when the box is closed. The puff also closes the openings 24 and the covering of these openings together with the seal formed between the rib 26 and the puff effectively prevents the loose powder passing into the box. The puff is held in this position by the cover of the box.

In use the powder container comprising the members 16 and 20 may be inserted in the body member 10 of the box and left loose therein, or the rim of the cover 20 may be made of a size to substantially fit the inside of the body 10 with a suitable frictional engagement to keep the container from falling out. To facilitate removal of the container from the box and also to facilitate separation of the closure 20 and the member 16 the rim 23 may be provided with a raised portion 27 for insertion of a finger nail. By insertion of the nail at this point, if the container is loose in the box, it may be easily lifted out and removed therefrom, and then the closure 20 may be easily separated from the cupped member 16 by merely passing the nail around between the flanges 17 and 23 a short distance. After the powder has been renewed the container may be quickly and easily sealed by merely pressing the two members together. If desired the cupped member 16 may be permanently fastened in the body member 10 of the box by any suitable means, such as cement, and in this arrangement the closure 20 may be as easily removed in the same manner by merely inserting a finger nail under the raised portion 27 and passing it around under the flange 23.

It will be apparent from the foregoing description that the construction is a very simple one, but that a container is provided for loose powder which may be used in place of the ordinary compact, and which will allow the user to use her favorite brand of powder in these boxes. Furthermore, it will be apparent that the renewal or change of powder may be quickly and easily effected, and a very effective seal is provided between the separable members of the container which will prevent leakage of the loose powder from the container.

Having thus set forth the nature of my invention, what I claim is:

1. In a vanity box, hinged cover and body sections, and an insert for one of said sections comprising a cupped powder container provided with a laterally projecting flange about its upper periphery, and a cover for closing the same having a depression to fit tightly into the top of the cupped member and having a laterally extending flange to rest on the flange of the cupped member, the center portion of the cover being flexible and resilient and provided with openings for passage of powder.

2. A vanity box comprising hinged body and cover sections, a mirror in the cover section, and a loose powder container forming an insert for the body section, said container having a flexible resilient top bowed upwardly at its central portion capable of being depressed by pressure and tending to spring back to its original position after the pressure is removed, and said top being provided with one or more openings for passage of powder.

3. A vanity box comprising hinged body and cover sections, and an insert for one of the sections comprising a loose powder container having a flexible resilient top bowed upwardly at its central portion capable of being depressed by pressure and tending to spring back to its original position after the pressure is removed, and said top being provided with openings for passage of powder from the container.

4. An insert for a vanity box comprising a loose powder container having a flexible resilient top bowed upwardly at its central portion capable of being depressed by pressure and tending to spring back to its original position after the pressure is removed, and said top being provided with openings for passage of powder from the container.

5. An insert for vanity boxes comprising a cupped member having a laterally extending flange about its upper periphery, and a closure for said member having a depressed central portion to fit tightly in the top of said cupped member and provided with a laterally extending peripheral flange to rest on the flange of the cupped member, the central portion of the closure being flexible and resilient and provided with openings for passage of powder.

6. An insert for vanity boxes comprising a cupped member having a laterally extending flange about its upper periphery, and a closure for said member having a depressed central portion to fit tightly in the top of said cupped member and provided with a laterally extending peripheral flange to rest on the flange of the cupped member, the central portion of the closure being flexible and resilient and provided with openings for passage of powder, and also provided with a

raised rib surrounding said openings to provide a seal with a powder puff seated on said closure.

7. A vanity box comprising hinged body and cover members, and a loose powder container forming an insert for one of said members, said container having a flexible resilient top wall bowed upwardly at its central portion capable of being depressed by pressure and tending to spring back to its original position after the pressure is removed, said top wall being provided with openings for passage of powder from the container, said top wall being also provided with a raised rib about said openings, and a puff held on said wall and against the rib by the other member to form a seal.

8. In a vanity box, hinged cover and body sections, a loose powder container forming an insert for one of said sections, and a closure for said container bowed upwardly at its central portion capable of being depressed by pressure and tending to spring back into its original position after the pressure is removed, said closure being provided with openings for passage of powder from the

container, said closure being also mounted to be raised from the container to permit refilling of the container.

9. An insert for vanity boxes comprising a cupped member forming a container for loose powder, said cupped member having a laterally extending flange about its upper periphery, and a closure for said member having a depressed central portion to fit tightly in the top of said cupped member and provided with a laterally extending peripheral flange to rest on the flange of the cupped member and form a seal therewith, said closure being provided with perforations for passage of powder from the container.

10. A box comprising a section which includes a container, said container having a top wall which includes a normally outwardly bowed, elastic portion, means for dispensing the contents of said container through said wall by pressing said portion inwardly, and a cover separably connected to said section adjacent said top wall.

In testimony whereof I affix my signature.

ANKER S. LYHNE.
